UNITED STATES PATENT OFFICE.

JOHN BURKHARDT, OF NEW YORK, N. Y.

CASTING-MACHINE.

1,308,926.

Specification of Letters Patent.

Patented July 8, 1919.

Application filed November 7, 1916. Serial No. 129,957.

To all whom it may concern:

Be it known that I, JOHN BURKHARDT, a citizen of the United States, and a resident of the borough of Manhattan, city, county, and State of New York, have invented certain new and useful Improvements in Casting-Machines, of which the following is a specification.

My invention relates to casting machines. It has for its object to simplify and improve casting machines and reduce the cost of manufacture of castings; to enable castings of different lengths to be made from a relatively small number of molds without the necessity of having a special set of molds for every length of casting; to provide new and improved means for cooling molds, and also for making long castings and for preventing such castings from irregular and uneven cooling and contraction during the molding operation; and also to improve casting machines in other ways herein specified.

It consists of the novel devices herein shown and set forth.

In the drawings accompanying this specification and forming a part hereof, I have illustrated my invention in its preferred form, which I will now proceed to describe.

Referring to such drawings,

Figure 1 is a side elevation of a casting machine embodying my invention;

Fig. 2 is a similar elevation on a large scale of a part of the machine shown in Fig. 1;

Fig. 3 is a vertical section on the line 3—3 of Fig. 4, and shows certain additional features not disclosed in Figs. 1 and 2;

Fig. 4 is an end elevation of the machine of Fig. 3, viewed from the right in the latter figure;

Fig. 5 is an end elevation of the same, viewed from the left in Fig. 3;

Figs. 6, 7 and 8 are details of the molds of Figs. 1 to 5; Fig. 6 being a plan of one mold block; Fig. 7 a side view taken from the inside or center of the mold block, as indicated by the arrow in Fig. 6; and Fig. 8 being a back view, the reverse of that of Fig. 7;

Fig. 9 is a detail showing a cooling chamber in one of the top mold blocks of Fig. 3;

Figs. 10 and 11 show details of the means for supporting cores; Fig. 10 being an elevation from the inside; and Fig. 11 a plan of Fig. 10;

Fig. 12 is a modification, showing means

to support the beveled portion of the mold block;

Fig. 13 is a detail, showing the dowel pin and recess used to register two mold blocks together;

Fig. 14 shows, in section, a modification of mold block adapted to cast a flange on a bar or cylindrical casting;

Fig. 15 is a view from the inside of a mold block, showing a modification, provided with gates for the metal and with circular horizontal joints between two mold sections;

Fig. 16 shows a modified form of apparatus for molding long castings, provided with a plurality of metal-pouring spouts and means for separating the lower mold blocks while the upper ones are being filled with metal;

Fig. 17 shows, in section, a mold, consisting of four parts or mold blocks, provided for eight guides, one set of four guides to separate two of the mold blocks from the other two, and the other set of guides to separate the mold blocks still remaining together;

Figs. 18 and 19 are modified forms of mold blocks for use in making small castings; Fig. 18 being an inner view in elevation of one mold block, and Fig. 19 a section on the line 19—19 of Fig. 18;

Fig. 20 illustrates still another modification.

Referring now to the machine illustrated in Figs. 1 to 5, 1 is the framework of the casting machine; 2, 2, are guides for the mold blocks, preferably made to diverge at the upper and lower parts of the machine, for purposes presently to be described; 3 and 4 are two series of mold blocks, the corresponding mold blocks in the two series being adapted to be brought together to form a complete mold, and molding spaces of any suitable shape being provided in the faces of these mold blocks, as shown at 5 in Fig. 6, adapted to register with the corresponding molding spaces in the corresponding blocks of the other series.

The mold blocks of each series are loosely arranged upon one another and upon the lowermost block of the series, all of the blocks of the series being supported and moved by that block as it moves.

Any suitable means of supporting the lowermost block of each series and for raising or lowering it may be provided, as well

as any suitable means for bringing the two series of mold blocks together and holding them together during the casting operation. The apparatus for these purposes as shown 5 consists of cables 6, one at the inner end of each series of mold blocks, each cable being secured at its lower end in any suitable way to the inner end, as at 7, of the lowermost blocks 3 and 4, and passing over the hooked 10 end 8 of the cross-bar 9. This cross-bar is supported on a hook 10 at the end of the cable 11, running over idle pulley 12, driving pulley 13, and having a counter-weight 14 at its end. Driving pulley 13 is driven, as 15 shown, by a sprocket wheel 15, provided with a handle 16 and a link chain 17, passing around sprocket 15 and sprocket wheel 18 of driving pulley 13. Counter-weight 14 keeps the cables taut and assists in raising 20 the molds. The latter are raised or lowered by the turning of handle 16 one way or the other.

The means shown for pressing the two series of mold blocks 3 and 4 together just 25 before and during the casting operation consist of a series of weighted levers 19, pivoted to the framework at 20, and carrying on their inner faces idle rollers 21, mounted in bearings 22 in the levers 19. Coöperating 30 with the levers and rollers are beveled edges 23 on the outer faces of the mold blocks 4, as clearly shown in Fig. 1. These bevels, as they are shown, extend outward toward the bottom of the outward faces of the 35 molds. The levers 19 are weighted at their inner ends, or to the right as viewed in Fig. 3, and tend to tilt clockwise. When the mold blocks are raised to casting position,—that shown in Fig. 3,—the beveled faces of 40 the molds 4 and the rollers and levers 19 cooperate to tilt the levers contraclockwise and force the mold blocks 4 against mold blocks 3 and the latter against guides 2, thus holding the two series of mold blocks tightly 45 together during the casting operation.

Any suitable means may be employed for feeding metal to the molds. In Fig. 3, I have shown a metal reservoir 24 located in the uppermost mold blocks, provided with 50 a gateway 25 leading to the molding spaces in each of the molds.

The means shown for separating the two series of molds from each other consist of guides 26, having a common knife edge 27 55 at their upper meeting edges. These guides 26 diverge, as shown in Fig. 3, and are substantially parallel to the diverging guides 2 at their lower ends. 28, 28, are water tanks into which the guides run. After the molding 60 operation, the two series of mold blocks are lowered, the knife-edge 27 and the guides 26 separating them, permitting the casting to fall out and to fall between the two tanks, while the two series of mold blocks are carried 65 into the water in the two tanks 28, 28,

respectively, as shown in dotted lines in Fig. 3. This cools the molds and also fills with water the water reservoirs 29, 29, contained in the highest mold blocks, shown in Figs. 3 and 9. These water reservoirs 29 in the 70 uppermost mold blocks are especially serviceable there because of the presence in these mold blocks of the metal reservoir 24. Such water reservoirs can, of course, be provided wherever desired. 75

The guides 2, 2, are caused to diverge at their upper ends, in order to permit the two series of molds to separate, as they will do when pulled upward above the position shown in Figs. 1, 2, and 3, to permit access 80 to the inner faces of the molding blocks for any purpose, as, for instance, for inserting cores. 30 is a stop to prevent the mold blocks from being pulled too high, and to act as a registering stop when the molds are 85 pulled upward from the water tanks. It will be understood, of course, that this is made removable in case it should be desired to pull the molds upward and to cause them to separate, as above described. 90

By means of the loose arrangement of mold blocks upon one another, as above described, castings of different length may be made without the necessity of making a special and complete set of molds for each particular length of casting. Castings of the usual ordinary lengths, and of almost any length, may be made from a relatively small number of molds. This effects a great saving in time and expense. In my improved 100 arrangement, moreover, no subgateways are required for leading the metal to the different molding spaces. 95

I preferably provide air spaces for cooling the molds. These are shown at 31. 105

In making long castings, difficulty is often experienced through a premature cooling and shrinking of the lower part of the casting while still in the mold and during the casting operation. The reason for this is 110 that the lower part of the casting is poured first and then the upper parts afterward. In a long casting, this takes an appreciable length of time, during which the lower part of the casting cools materially faster than 115 the upper part, often resulting in injury to the casting or breaking or cracking of the casting. In Fig. 16, I have illustrated a combination of means for preventing this result. Here the mold blocks are moved 120 during the casting operation, and during that operation the lower blocks are separated to free the lower part of the casting from the mold blocks, while the upper part of the casting is still being poured. I have 125 shown this arrangement in Fig. 16 only diagrammatically, without all of the details, such as the means for moving the mold blocks continuously during the operation. Of course, any suitable means could be em- 130

ployed for this and any other suitable details for other parts of the apparatus. The lower part of the casting 32 being made is shown as projecting downward, being freed 5 from the lower mold blocks. It will be understood that the upper part of this same casting, which is shown as a pipe, is in process of being formed.

While in this arrangement any suitable 10 means may be employed for supplying the metal to the molds, I have shown a plurality of metal reservoirs evenly spaced throughout the length of the mold blocks. These are shown in the form of horns 33, 15 projecting from the side of the mold blocks. Metal is poured into these horns at the proper time during the process, and flows thence to the molding spaces.

In Figs. 10 and 11, I have shown means 20 for readily supporting cores. As there shown, 34 is a core supported in hooks 35, secured to the mold blocks. 36 represents a sub-gateway for leading the metal to the molding space 37.

25 In Fig. 12, 38 is a support for the beveled section 39 of a mold block, in order to give it sufficient strength at its middle portion, and to allow for expansion and contraction without cracking.

30 I preferably provide dowel pins and holes in the different mold blocks, in order to register them with one another, both when the mold blocks are placed one upon another in a series, and when the mold block of one 35 series comes into engagement with its corresponding mold block of the other series. In Fig. 13, I have illustrated this. 40 is a dowel pin secured in one of the mold blocks and entering a hole or seat 41 for it in the 40 adjoining mold block. This causes contiguous mold blocks to register exactly with each other.

In Fig. 14 I have shown mold blocks 45 adapted to cast a flange on a bar or cylindrical casting. A molding space for forming this flange is shown at 42.

Fig. 15 represents a number of mold blocks, viewed from the inside, for making cylindrical castings, and showing curved 50 horizontal joints between the different mold blocks. In this figure, the molding spaces are shown at 43, the metal reservoir at 44, and the gateways at 45. Here a portion of the surfaces of the adjoining mold blocks is 55 curved, as shown at 46.

In Fig. 17 I have illustrated a mold composed of four mold blocks 47. The molding spaces are represented at 48; 49 are the metal-pouring spouts; 50 are eight spaces 60 for holding eight guide rails for controlling the movements of the four mold blocks composing the mold. These guides are not shown, but are so arranged as to separate two of the mold blocks from the other two, 65 dividing the mold into two parts, and then

each half is divided into its two halves for the discharge of the cast materials.

Figs. 18 and 19 represent modifications of mold blocks for use in making small castings. 51 represents the molding spaces in 70 a small molding block 54; 52 the gateways. The small block 54 with this molding space in it is secured to the face of the main part 53 of the molding block 54 by means of bolts 55 and nuts 56, as shown. By this arrangement, small mold face sections may be used 75 on the same solid part 53 of the mold block. This will make it easier and cheaper to make the active part of the mold block, dispensing with great weight, and effecting a saving in 80 the iron or steel employed.

In Fig. 20, I have shown a modification, in which a metal reservoir is provided in the stationary part, the mold blocks being adapted to be brought up from beneath into 85 connection with it. 57 represents the stationary part provided with the metal reservoir 58. 59 are passageways for the metal. The different mold blocks of a series are represented at 60, and their molding spaces at 90 61. 62 are the gateways for the metal. I have shown these preferably as provided at their upper ends with saucer-shaped expansions 63 for catching and preventing the escape of the metal. 64 are dowel pins for 95 registering the mold blocks with the stationary part 57. These dowel pins enter holes 65 in the upper mold blocks 60, as already explained. The shoulders on pins 64 act as spacers between part 57 and the uppermost 100 mold block.

In order to provide against undue expansion of the face of the mold block, due to the excessive heat, and to prevent the mold block from warping, I preferably split or 105 divide the inner face of the mold block to permit of such expansion without affecting the mold itself. This is illustrated in Fig. 6, where I have provided a split or division at the points 66. These are shown running 110 from the inner face of the mold block and connecting with the air spaces or chambers 81.

In this figure and Fig. 7 I also show a vent 67 running from the molding space to 115 the outer air, for the discharge of gas.

If desired, the inner face of the mold block may be hinged, as shown at 68 in Fig. 12.

What I claim as new and desire to secure by Letters Patent is:—

1. In a casting machine, the combination of two series of mold blocks adapted, when brought together, to coöperate with each other to form complete molds, the blocks of each series loosely arranged upon one another, means connected with the lowermost block of each series for supporting, raising or lowering the said series, means for forcing the corresponding mold blocks of the two series together for the casting opera- 125 130 135

tion, and means for separating them after the operation to discharge the cast articles.

2. In a casting machine, the combination of two series of mold blocks adapted, when brought together, to coöperate with each other to form complete molds, the blocks of each series loosely arranged upon one another, means connected with the lowermost block of each series for supporting, raising or lowering the said series, beveled surfaces on the outer faces of the mold blocks of one series, and weighted pivoted arms carrying rollers adapted to be struck by the beveled edges as the molds move into casting position and to move the pivoted arms into line with the mold to exert pressure to force it against its corresponding mold block of the other series.

3. In a casting machine, the combination of two series of mold blocks adapted, when brought together, to coöperate with each other to form complete molds, the blocks of each series loosely arranged upon one another, means connected with the lowermost block of each series for supporting, raising or lowering the said series, beveled surfaces on the outer faces of the mold blocks of one series slanting downwardly and outwardly, pivoted arms weighted at their ends toward the mold blocks and carrying rollers adapted to be struck by the beveled surfaces as the mold blocks rise and to be carried upward so as to exert pressure upon the mold blocks when casting position is reached to force the mold blocks of one series against the mold blocks of the other series, and means for separating the mold blocks of the two series to discharge the cast articles.

4. In a casting machine, the combination of two series of mold blocks provided with grooves in their outer edges adapted, when brought together, to coöperate with each other to form complete molds, the blocks of each series loosely arranged upon one another, means connected with the lowermost mold block of each series for lowering and raising the mold blocks, guide rails engaging with the grooves in the outer edges of the mold blocks of each series for guiding the mold blocks, said guide rails diverging or separating toward their lower end and passing into water tanks, inner guide rails opposite the lower diverging portion of the above-mentioned guide rails and substantially parallel thereto and leading into the water tanks, the said inner guide rails meeting at the top in a knife edge underneath the dividing line between the two series of mold blocks for separating the mold blocks of the two series when lowered, and means for forcing the mold blocks of one series against the mold blocks of the other series when the mold blocks are in casting position, also arranged and combined that when the mold blocks are moved into casting po-

sition they will be forced and held together and when lowered will be separated to discharge the cast articles and the mold blocks will be guided into the water tanks to be cooled.

5. In a casting machine, the combination of two series of mold blocks adapted, when brought together, to coöperate with each other to form complete molds, the blocks of each series loosely arranged upon one another, means connected with the lowermost mold block of each series for lowering and raising the mold blocks, guide rails engaging with grooves in the outer edges of the mold blocks of each series for guiding the mold blocks, said guide rails diverging or separating toward their lower end and passing into water tanks, inner guide rails opposite the lower diverging portion of the above-mentioned guide rails and substantially parallel thereto and leading into the water tanks, the said inner guide rails meeting at the top in a knife edge underneath the dividing line between the two series of mold blocks for separating the mold blocks of the two series when lowered, and means for forcing the mold blocks of one series against the mold blocks of the other series when the mold blocks are in casting position, a metal reservoir in the uppermost mold blocks and water chambers in the said blocks, all so arranged and combined that when the mold blocks are moved into casting position they will be forced and held together and when lowered will be separated to discharge the cast articles and the mold blocks will be guided into the water tanks to be cooled and to fill the water cooling chambers in the mold blocks.

6. In a casting machine, the combination of two series of mold blocks adapted, when brought together, to coöperate with each other to form complete molds, the blocks of each series loosely arranged upon one another, means connected with the lowermost mold blocks for raising or lowering the mold blocks of each series, guide rails coöperating with grooves in the outer ends of each series of mold blocks for guiding the mold blocks, said guide rails diverging toward their upper and their lower ends to permit access to the inner molding spaces of the two series of mold blocks when they are separated at the upper diverging ends of the guide rails and to permit the mold blocks of the two series to separate to discharge the cast articles when they separate at the divergence of the guide rails at their lower ends.

7. In a casting machine, the combination of two series of mold blocks adapted, when brought together, to coöperate with each other to form complete molds, the blocks of each series loosely arranged upon one another, means for raising and lowering the

mold blocks, guides for controlling the movement of the mold blocks, said guides diverging at the top and bottom so that when the blocks are pulled up toward the top or moved 5 down toward the bottom of the guides they will separate, and when they are moved to the middle portion of the guides the two series of mold blocks will approach each other to bring corresponding mold blocks together, 10 and means for pressing the mold blocks together at such central point.

8. In a casting machine, the combination of two series of mold blocks adapted, when brought together, to coöperate with each 15 other to form complete molds, the blocks of each series loosely arranged upon one an-

other, means for raising or lowering the series of mold blocks and for bringing them together for the casting operation, and means for separating the lower mold blocks 20 while the molding operation is still proceeding in the upper blocks, whereby the lower part of the casting will be removed from the molds while the upper part of the casting operation is proceeding, whereby long 25 lengths of castings may be made without irregular and undue cooling and contraction in different parts of the casting.

In testimony whereof, I have signed my name to this specification.

JOHN BURKHARDT.
